DESIGN FOR A WINDOW VENTILATING FAN

Taylor Barnes, Shreveport, La.

Application March 8, 1946, Serial No. 127,212

Term of patent 7 years

(Cl. D62—4)

To all whom it may concern:

Be it known that I, Taylor Barnes, a citizen of the United States and a resident of Shreveport, Parish of Caddo, and State of Louisiana, have invented a new, original, and ornamental Design for Window Ventilating Fans, of which the following is a specification, reference being had to the accompanying drawings, forming a part thereof.

Figure 1 is a front elevational view of a window ventilating fan showing my new design.

Figure 2 is a rear elevational view of the window ventilating fan and

Figure 3 is an enlarged fragmentary sectional view taken on line 3—3 of Figure 1.

I claim:

The ornamental design for a window ventilating fan, as shown.

TAYLOR BARNES.
